UNITED STATES PATENT OFFICE.

JOSEPH S. WOOD, OF BROOKLYN, NEW YORK.

GAS-ENGINE.

SPECIFICATION forming part of Letters Patent No. 363,497, dated May 24, 1887.

Application filed December 7, 1885. Renewed April 22, 1887. Serial No. 235,801. (No model.)

To all whom it may concern:

Be it known that I, JOSEPH S. WOOD, of Brooklyn, in the county of Kings and State of New York, have invented certain new and useful Improvements in Gas-Engines, of which the following is a specification.

This invention relates to improvements in gas-engines of that class in which a mixture of gas and air is drawn into the cylinder by the outgoing stroke of a piston and then exploded, so that the piston is moved forward to its full length by the motion imparted to the driving-shaft.

The object of the invention is to simplify the construction of this class of engines and improve the operating parts by preventing any escape of the gas and air mixture on the opening and closing of the valves and reducing the noise of the explosions; and the invention consists of a cylinder the head of which is provided with a supply-port for the gas and air mixture and an ignition-port, which ports register at the proper time with similar ports of a laterally-reciprocating slide-valve and with ports of a transverse guide-piece of the head. The head of the cylinder is further provided with a regulating air-port having an interior check-valve for the additional supply of air required for combustion. A transverse channel at the inside of the head connects the air and gas mixture to the ignition-port, so as to form a mixing chamber and facilitate the explosion of the gas and air mixture in the cylinder.

In the accompanying drawings, Figure 1 represents a side elevation of my improved gas-engine. Fig. 2 is a plan; Fig. 3, an end elevation of the same; Fig. 4, an end view of the cylinder-head drawn on a larger scale. Figs. 5, 6, and 7 are vertical transverse sections of the cylinder-head, respectively on lines *x x*, *y y*, and *z z*, Fig. 4; and Fig. 8, a vertical transverse section of the cylinder on line *c c*, Fig. 5.

Similar letters of reference indicate corresponding parts.

A in the drawings represents the supporting-frame of my improved gas-engine; B, the cylinder, and B' the head, which is screwed tightly to one end of the same. The cylinder 50 B is open at the opposite end for the piston-rod C, which is connected to a crank-shaft, D, having a fly-wheel, D'. The head B' has a transverse recess, b, and a transverse guide-

piece, B², that serves to guide a laterally-reciprocating slide-valve, E, which is pivoted to the longer arm of a fulcrumed bell-crank lever, E', the shorter arm of which is pivoted by a connecting-rod, E², to the T-shaped head of an oscillating arm, E³, that is pivoted to the frame A, as shown in Fig. 1. The opposite end of the T-shaped head of the oscillating arm E³ is provided with an anti-friction roller, e, that is held in contact with an eccentric cam, E⁴, of the driving-shaft D, by a spiral spring, e', attached to the arm E³ and the frame A, as shown in Fig. 1. The cam E⁴ operates the slide-valve E by the intermediate mechanism described, and imparts the required motion thereto. The transverse guide-piece B² is provided with a gas and air inlet port, b', which opening registers with a corresponding opening, b², of the slide-valve E, and an opening, b³, in the head of the cylinder. The gas and air ports are connected with a gas-supply pipe, F, by an intermediate valve-casing, F', having a perforated diaphragm, f, the opening of which is closed by a check-valve, f', when the explosion takes place.

The valve-casing F' connects by a small pipe, f², with the inlet ports b' b² b³, the end of the pipe f² being ground off and accurately fitted to the slide-valve E, so that the latter closes the same and prevents the escape of gas through the air supply port f³ when the port b² of the valve is not in register with the ports b' b³. The small gas-supply pipe f² is surrounded by a larger air-pipe, F², having an air-supply port, f³, through which the air is drawn into the cylinder with the gas. Through the gas and air ports b', b², b³, and f³ the gas and air are drawn in by the suction of the piston when the same is in its outgoing stroke, while when the same is in its return-stroke the products of combustion are ejected through said ports and the port f³ to the atmosphere, the gas-check valve f' being then closed by the pressure of the gases of combustion on the same, so as to prevent the waste gases from passing into the regulating gas-bag.

The guide-piece B², slide-valve E, and head B' are provided sidewise of the gas and air inlet ports with coinciding ignition-ports d' d² d³, as shown in Figs. 4 and 7. The port d³ is closed at the inside of the head B' by a check-valve, d⁴, that closes the ignition-ports at the moment when the explosion takes place.

Below the ignition-port d' an ignition-burner, d^4 , is arranged, the flame of which is sucked in at the moment when the ignition-ports d' d^2 d^3 are in register with each other, so as to 5 ignite the air and gas mixture in the cylinder and cause the explosion of the same. A chimney, d^5 , is attached to the guide-piece B^2 vertically above the slide-valve, to exert a draft on the ignition-flame. The cylinder head B' 10 is further provided above the slide-valve E with an auxiliary air-supply port, a , that has at the inside a check-valve, a' , and at the outside a fulcrumed slide-piece, a^2 , having a perforation, a^3 , at one end, which registers with 15 the auxiliary air-port a , while the pointed opposite end of the adjustable slide-piece a^2 may be adjusted along a scale, (shown in Fig. 4,) so that the slide-piece a^2 can be set for opening partly or entirely the air-port a , and supply 20 thereby the required extra quantity of air to the gas and air mixture in the cylinder to produce the complete combustion of the same.

Across the inlet-port b^3 , at the inside of the head B' , extends a sheet-metal plate, g , that 25 abuts by one end against the wall of the cylinder, while the other terminates near the ignition-port d^3 . The plate g forms with the head B' a mixing-chamber for the gas and air supplied by the ports b' b^2 b^3 , and as a channel for 30 conducting the gas and air mixture to the ignition-opening. The plate g also serves to deaden to some extent the noise of the explosion, as it acts as a kind of shield for the inlet-ports at the moment of the explosion.

35 The operation of the engine is as follows: The burner is lighted and the fly-wheel of the engine turned once or twice by hand. When the piston commences its outgoing stroke, the inlet-port b^2 of the slide-valve E is in register 40 with the inlet-ports b^3 b' of the cylinder-head B' and guide-piece B^2 , so that the air and gas mixture can be sucked into the interior of the cylinder. The air and gas as they enter into the cylinder are intimately mixed in the mixing-chamber formed by the plate g , and are 45 ignited at the moment when the ignition-port d^2 of the slide-valve registers with the ignition-ports d^2 and d' of the cylinder-head and guide-piece B^2 . When the ignition of the air 50 and gas mixture takes place, the inlet-port of the slide-valve is not in register with the ports of the head and guide-piece, so that no gases of combustion can escape. By the outgoing stroke of the piston the additional quantity 55 of air required for the combustion of the air and gas mixture is sucked in through the auxiliary air-port a . The check-valves of the auxiliary air-port and of the ignition-port are closed by the pressure of the products of combustion, 60 so as to prevent the escape of any part of the same through said ports. On the return stroke of the piston the products of combustion are exhausted through the inlet-ports b^3 , b^2 , b' , and f^3 , while simultaneously the check-valve f' 65 closes the opening in the diaphragm of the valve-casing, owing to the pressure of the products of combustion on the check-valve. By

the force of the explosion the piston is moved forward, so as to complete its stroke and carry the crank-shaft over its dead-point, it being 70 returned by the fly-wheel, so that the products of combustion can be exhausted. On the return motion of the slide-valve the inlet-ports are placed in register again, so that on the outgoing motion of the piston a new charge of 75 gas and air is sucked in again, which is exploded at the proper time, and so on, imparting thereby rotary motion to the driving-shaft.

The advantages of my improved construction of gas-engine are, first, that all the ports 80 are located at the head of the cylinder and none in the cylinder itself, whereby the cleaning and repairing of the same is facilitated, as access is given to all the ports on removing the head; secondly, a more thorough mixing 85 of the air and gas takes place in their passage to the cylinder by the plate or shield that extends transversely over the inlet-ports of the cylinder-head; and, thirdly, that by the auxiliary air-port and its regulating-slide the exact quantity of air can be supplied to the gas and air mixture, according to the kind and quality of gas supplied to the engine, whereby 90 a more perfect combustion of the explosive gas and air mixture takes place.

Having thus described my invention, I claim 95 as new and desire to secure by Letters Patent—

1. The combination of a cylinder, a cylinder-head having a transverse guide-piece, a laterally-reciprocating slide-valve guided by 100 the head and guide piece, said head, slide-valve, and guide-piece having gas and air inlet ports and ignition-ports, and a transverse plate or box extending over the inlet-port at the inside of the cylinder-head, so as to form 105 a mixing-chamber for the air and gas, substantially as set forth.

2. The combination of a cylinder, a cylinder-head having an exterior guide-piece, a laterally-reciprocating slide-valve, gas and air 110 inlet ports, and ignition-ports arranged in said cylinder-head, guide piece, and slide-valve, and an auxiliary air-port arranged in said head and provided with an interior check-valve and an exterior regulating device, substantially as 115 set forth.

3. The combination of a cylinder, a cylinder-head having a transverse guide-piece, a laterally-reciprocating slide-valve, gas and air inlet ports and ignition-ports arranged in the 120 guide-piece and slide-valve and cylinder-head, a gas-supply pipe having a partitioned valve-casing and check-valve, an air-pipe having an air-port, and a gas-pipe extending through the air-pipe to the slide-valve, whereby the slide-valve cuts off the gas-supply at the moment when the inlet-ports are out of register, substantially as set forth.

In testimony that I claim the foregoing as my invention I have signed my name in presence of two subscribing witnesses.
